(57) **CLAIM**

The ornamental design for a case for electronic device, as shown and described.

DESCRIPTION

FIG. 1 is a rear perspective view of a case for electronic device;
FIG. 2 is a front elevation view of the FIG. 1. device;
FIG. 3 is a rear elevation view of the FIG. 1. device;
FIG. 4 is a right-side elevation view of the FIG. 1. device;
FIG. 5 is a left-side elevation view of the FIG. 1. device;
FIG. 6 is a top plan view of the FIG. 1. device;
FIG. 7 is a bottom plan view of the FIG. 1. device; and,
FIG. 8 is a front perspective view of the FIG. 1. device.
The broken lines are for illustration only and form no part of the claimed design.
